UNITED STATES PATENT OFFICE

2,435,116

BLASTING CARTRIDGE

Frank H. Armstrong, Chicago, Ill., assignor to
Armstrong Coal Break Company, a corporation
of Michigan

Application November 28, 1945, Serial No. 631,303

5 Claims. (Cl. 102—25)

1

This invention relates to blasting cartridges wherein highly compressed non-explosive gas is used as a material-breaking medium.

The primary object of the invention is to provide an improved blasting cartridge for use in coal mines and the like, wherein the cartridge may be operated at will by a trigger device extending out of the casing, and the surrounding material may be broken loose without employing any igniting means.

A further object of the invention is to provide a blasting cartridge with an improved valve means, which will open quickly when released, with little throttling action, and which will automatically close the chamber after discharge, so as to prevent extraneous material from entering the cartridge. Other objects and advantages of the invention will be understood from the following description and the appended claims.

The invention is illustrated in a preferred embodiment in the accompanying drawing, in which—

Figure 1 is a broken longitudinal sectional view of a blasting cartridge embodying the invention; Fig. 2, a fragmentary longitudinal sectional view, taken as indicated at line 2—2 of Fig. 1; Fig. 3, a view similar to Fig. 1, but showing the cartridge while being discharged; Fig. 4, a vertical sectional view, taken as indicated at line 4—4 of Fig. 1; and Fig. 5, a sectional view taken as indicated at line 5—5 of Fig. 2.

In the embodiment illustrated a long tubular casing 6 is closed at one end by means of a threaded connection with a cap 7, through which extends a hollow trigger member 8 surrounded by packing 9 held by a stuffing gland 10. The trigger member has a conduit 11 through which air may be introduced into the casing from a flexible tube 12 provided with a coupling 13. The trigger member is preferably provided with a collar-like stop 14, so that it may make but a limited travel with respect to the casing.

The casing also has a cylinder portion 15, provided with a series of laterally extending discharge ports 16, which are normally closed by a sleeve-like valve member 17, having a skirt 18. As the gas pressure in the casing may be about eleven thousand pounds per square inch, it is necessary that a very effective sealing means be provided. To accomplish this, a thin metal sleeve 19 is gripped between a shoulder on the cylinder 15 and the threaded portion of the casing 6, as shown at 20. This member provides an annular cavity which receives the skirt 18. The valve member 17 has a differential head 21 having a

2

larger area on the right, as viewed in Figs. 1 and 3, than on the left. This differential head urges the valve to open position under the influence of the pressure in the cartridge. The outer end of the cylinder 15 is provided with a screw plug 22 whose inner end is bifurcated at 23 to receive a pair of locking dogs 24, which have beveled ends 25, to engage the chamfered end of the valve member 17. The locking members are 10 yieldingly urged to extended position by means of a compression spring 26. The trigger member 8 extends through an aperture in the differential head 21, and through a leather backing 27 to a position between the locking dogs 24, so as to hold the valve member 17 in closed position, as shown in Fig. 1. The leather backing 27 is secured to the ends 23 of the plug member by screws 28. A compression spring 29 is provided in the valve member and bears against the differential head 20 21, so as to urge the valve to closed position. As shown in Fig. 2, the plug member 22 is also provided with an aperture 30, which is open to atmosphere and permits access to the lower end of the valve member 17. If the latter should happen to stick in open position, a small rod may be inserted into the opening 30 and the valve pressed to closed position, so that the trigger may be re-engaged with the dogs 24. Thus it will be understood that the spring 29 is not necessary for operation of the device, but it is preferred to use it so that the ports 16 will be closed automatically after the cartridge is discharged, and will prevent material from getting into the casing and interfering with its subsequent operation.

35 To operate the device, a hole is drilled in the material which is to be broken, and the cartridge is fully inserted and held securely in position by driving a small wedge between the cap 7 and the hole. Gas, such as air, is then admitted through 40 the tubing 12 until a very high pressure is obtained within the casing. When it is desired to discharge the cartridge, an outward pull on the trigger member 8 will release the dogs 24, cause the valve member 17 to jump to the position shown in Fig. 3, and the high pressure gas will be discharged through angular lateral ports 16. Immediately after discharge, the spring 29 will cause the valve to return to closed position, and the spring 26 will move the dogs 24 to a position 45 where the trigger may be returned to holding position.

If desired, the trigger member and tubing may be connected to a long stroke air cylinder. When it is desired to operate the cartridge it is merely necessary to have the air cylinder pull on the

trigger member, and as the pulling continues during and after the discharge, the cartridge will be drawn clear of the broken material, so that no digging is necessary to have it available for the next operation. While it is preferred for safety reasons to charge the cartridge after it has been installed in the hole to be blasted, it will be understood that the cartridge can be pre-charged, if desired.

The foregoing detailed description is given for clearness of understanding only, and no unnecessary limitations should be understood therefrom, for some modifications will be obvious to those skilled in the art.

I claim:

1. A blasting cartridge comprising: a round hollow casing provided with laterally extending discharge ports; a sleeve-like valve in said casing adapted to close said ports and provided with a differential head whereby high gas pressure in the casing urges said valve to open position; expansible locking dogs in said casing for releasably holding the valve in closed position; a removable plug member in one end of the casing for receiving said dogs, and said plug member having an opening for permitting contact with said valve from outside of said casing; and a trigger member slidably mounted in the other end of the casing, extending through the differential head, and adapted to hold the dogs releasably in locking position.

2. A blasting cartridge comprising: a closed hollow casing provided with laterally extending discharge ports and adapted to receive an expansible gas under high pressure; valve means for closing said ports and urged to open position by gas pressure in said casing; locking means in said casing for holding said valve means in closed position; and a trigger member extending through the casing to said locking means for releasing the locking means at will; said valve means including a differential piston having a skirt for closing the discharge ports, and the casing being provided with a fixed thin metal sealing sleeve forming an annular cavity to receive said skirt when in closed position.

3. A blasting cartridge comprising: a closed hollow casing provided with laterally extending discharge ports and adapted to receive an expansible gas under high pressure; valve means for closing said ports and urged to open position by gas pressure in said casing; locking means in

5 said casing for holding said valve means in closed position; and a trigger member extending through the casing to said locking means for releasing the locking means at will; said locking means comprising a pair of expansible dogs which may be held in expanded locking position by the trigger member.

4. A blasting cartridge comprising: a closed hollow casing provided with laterally extending discharge ports and adapted to receive an expansible gas under high pressure; valve means for closing said ports and urged to open position by gas pressure in said casing; locking means in said casing for holding said valve means in closed position; and a trigger member extending through the casing to said locking means for releasing the locking means at will; said locking means comprising a pair of expansible dogs which may be held in expanded locking position by the trigger member, and a spring for urging said dogs to expanded position to facilitate reinsertion of said trigger member between them when the valve means is closed.

5. A blasting cartridge comprising: a closed hollow casing provided with laterally extending discharge ports and adapted to receive an expansible gas under high pressure; valve means for closing said ports and urged to open position by gas pressure in said casing; locking means in said casing for holding said valve means in closed position; and a trigger member extending through the casing to said locking means for releasing the locking means at will; said locking means comprising a pair of expansible dogs which may be held in expanded locking position by the trigger member, and said trigger member being provided with a stop within the casing to limit complete withdrawal from said casing.
